United States Patent Office

DANIEL J. TITTLE, OF ALBANY, NEW YORK, ASSIGNOR TO ALBI M. TITTLE,
OF THE SAME PLACE.

Letters Patent No. 79,282, dated June 23, 1868.

IMPROVEMENT IN HORSE-POWER.

The Schedule referred to in these Letters Patent and making part of the same.

TO ALL WHOM IT MAY CONCERN:

Be it known that I, DANIEL J. TITTLE, of the city and county of Albany, State of New York, have invented an Improvement in Horse-Powers for Railroads, &c., whereby cars can be drawn ahead, or backed up, or stopped, at the will of the driver in charge; and I do hereby declare that the following is a full, clear, and exact description thereof, reference being had to the accompanying drawings, forming a part of this specification, and to the letters of reference marked thereon, the same letters indicating like parts, in which—

Figure 1 represents a vertical view from above, with the upper portion of the endless-tread apron removed.

Figure 2 represents a longitudinal cross-section of invention.

Figure 3 represents a lateral cross-section, front of the centre of the same.

Figure 4 represents two pieces of the endless apron, viewed from their inner sides.

The nature of my invention consists of an endless-tread apron, furnished with two sets of cogs. One set of the said cogs are placed at the ends of the tread-pieces, and said tread-pieces are furnished with but two of these cogs, one at each end. The other set of cogs are placed midway between the ends of the tread-pieces in a single row, and each piece is furnished with several such centre cogs. The two outside rows of cogs work on the front and rear carrying-wheels. The shaft of the front carrying-wheel is provided with a gear-wheel, which works into another gear-wheel, fixed to the axle of the drive-wheels. The gear-wheel of the carrying-wheels' shaft is fixed by a feather from turning, and can move in a lateral direction from the gear on the drive-wheel axle, and by means of a suitable lever they may be thrown out or in gear at pleasure.

The centre row of cogs (on the tread-pieces) mesh in and work direct on the drive-wheels when thrown in gear by a lever, which operates one or more rollers beneath the endless tread, and which press the said cogs into the drive-wheel gear. A pan is placed under the whole length of the endless tread, which catches the dung and urine of the animals working the machine. Suitable holding-clamps, provided with set-bolts, and mash-nuts, are placed at proper points, front and back, on the sides, by which the required inclination of the tread is held securely.

To enable others skilled in the art to make and use my invention, I will proceed to describe it in reference to the drawings, and letters of reference marked thereon.

A A, figs. 1, 2, 3, represent the supporting-timbers of machine, to which are attached the journal-boxes *a a* of the carrying-wheels' shafts, figs. 1 and 3. To the said shafts *b b* are attached the carrying-wheels *c c c' c'*. These carrying-wheels have in them, around their outer edges, the notches *d d*.

The endless tread B, figs. 1 and 2, is constructed of many tread-pieces, *e e*, jointed together, as *e e* in fig. 4. The said tread-pieces may be made wholly or in part of iron or wood, or both. On the inner side of the tread-pieces, next to the links *f f*, fig. 4, are placed the single cogs *g g*. These cogs work in the notches *d d*, and operate the carrying-wheels *c c*, fig. 2, moving them in the direction indicated by the arrows marked thereon.

Placed on the shaft *b* of the carrying-wheel *c*, figs. 1, 2, and 3, is the gear-wheel *K*, which is prevented from turning on the shaft by a feather. The said gear *K* can move in a lateral direction, and be thrown in or out of gear with the second gear-wheel *M*, by means of the lever *i*, acted upon by a second lever, *n*, and draw-bar *o*, figs. 1 and 2.

The cogs *h h h*, on the tread-pieces *e e*, fig. 4, are placed near midway between the outer cogs *g g*, and may, at will, operate in the cogs of the gear *M*, fig. 2, from the lower side, and will turn the said gear-wheel *M* in a direction contrary to that of gear-wheel *K* when it is in motion. The cogs *h h* are not to be made to work in the cogs of the gear *M* only when the wheel *K* is thrown out of gear from the wheel *M*, except when it is desirable to stop the machine.

The gear-wheel *M* is attached to the shaft *p* of the drive-wheel *D*, and will cause the said drive-wheel *D* to revolve forward or backward, according as it is driven by the gear-wheel *K*, or by the cogs *h h* of the endless tread B, figs. 1 and 2.

To throw the cogs h h in work with the gear-wheel M, the rollers r r , placed under the endless tread, figs. 2 and 3, are thrown upward against the face of the said tread; by means of the lever S, connected with the roller-holding bars t t by the link w and ear v , fig. 2; and when thrown in gear, the said tread is kept in contact with the said gear M by the lever S being held down by the handled hook W' , moved in direction of the red dotted lines in fig. 2. The holding-rollers r r are placed in a suitable bar-frame, t , which traverses the under side of the machine obliquely, as is indicated by the red dotted lines in fig. 1, and is connected to the timbers A A by a joint hinge starting down therefrom on the opposite side from the lever S.

F F F F is the usual framework of a truck, to which are attached the usual coupled wheels D D D' D' by proper axle-boxes. The shafts or axles of the said wheels pass through between the upper and lower sides of the endless tread, as is shown in figs. 1 and 2. And the tread-power is sustained by the truck-timbers F F by the means of the clamping holders x x' , figs. 1 and 3, placed front and back on each side, and held secure by the bolts and their nuts y y . By means of the holding-clamps x x' , and the binding-bolt and its nut y , the incline of the endless tread can be adjusted and secured.

A pan, Z, is placed under the endless tread to catch the excrements that may fall from the animals, and is supported from the tread-timbers A A, or may be supported by the truck-timbers F F.

The usual side-piece (not represented in the drawings) may be placed and attached as is generally done.

To operate this power, the animals are placed on the tread B, when their weight and draught will give to the tread a movement in direction of the arrows, fig. 2. The tread carried by the wheels c c c' c' , which move in the said direction, is also carried and supported between the two ends by the bearing rollers q q , let in and supported by the upper timber A A. The gear-wheel K, being attached to the shaft of the carrying-wheel c , has a movement in the same direction as the tread; and when the said gear-wheel K is thrown in gear with the wheel M by the lever n , the gear-wheel M will have a movement in a contrary direction, and will carry with it the drive-wheel D in direction of the arrows in fig. 2. When the wheel K is thrown out of gear from the wheel M, and the rollers r r are thrown up by the lever S, the middle line of cogs, h h , will be thrown in gear with the wheel M, and reverse its former motion and cause the drive-wheel to turn back. If the wheel c be thrown in gear with the wheel M, while the said wheel M is in gear with the cogs h h of the tread, then the whole machine will be brought to rest.

The advantages of these improvements are these:

First. A simple reversible tread-power is produced which is completely under the control of the tender.

Second. Cars can be drawn or propelled forward, or backed, or stopped with ease.

Having described my invention, what I claim, and desire to secure by Letters Patent, is—

1. The endless tread, composed of the pieces e e , and furnished with the links f f , outer cogs g , and middle cogs h h , and all in combination with the said tread-pieces e e , substantially as and for the purpose set forth and described.
2. The gear-wheel K, working on the shaft of the carrying-wheels c , in combination with the levers i and n , and connecting-bar o , or their equivalents, as and for the purpose set forth and described.
3. The gear-wheel M, in combination with the drive-wheel D, or its equivalent, and the gear-wheel K, substantially as and for the purpose set forth and described.
4. The rollers r r , with their supporting-bars t t , or their equivalents, in combination with the lever S and its link w and connecting-ear v , or their equivalents, as and for the purpose set forth and described.
5. The holding-clamps x x' , and binding-bolt and nut y , or its equivalent, as and for the purpose set forth and described.
6. The pan Z, arranged as and for the purpose set forth and described.

DANIEL J. TITTLE.
